UNITED STATES PATENT OFFICE

2,210,873

TELEPHONE SYSTEM

George Thomas Baker, Liverpool, England, assignor to Associated Telephone & Telegraph Company, Chicago, Ill., a corporation of Delaware

Application August 30, 1937, Serial No. 161,580
In Great Britain September 10, 1936

8 Claims. (Cl. 179—7.1)

The present invention relates to telephone systems and is more particularly concerned with the provision of zone metering facilities in systems not employing register-controllers. From an economic standpoint it is preferable to locate the multi-fee metering equipment in a common group and to associate a set of equipment with an outgoing junction relay set, for example, when desired. Hitherto, however, this arrangement in a simple form has not been possible owing to lack of time in an interdigital pause to ensure the performance of both the normal switch hunting operation for a free junction relay set and in addition the extra hunting operation required for an idle multi-metering equipment. The chief object of the invention is to overcome this difficulty by the use of a so-called mechanical impulse repeater by which is meant a registering and sending device in which the length of a train of outgoing impulses is determined by a mechanical marking corresponding to the received train rather than by an electrical marking as is more usual.

According to one feature of the invention in a telephone system arranged for zone metering an outgoing trunk has associated with it a mechanical impulse repeater arranged to store incoming impulses and re-transmit them only after a set of common auxiliary equipment has been associated with the trunk.

According to another feature of the invention in a telephone system employing mechanical impulse repeaters for impulse repetition over junction lines the transmitting operation of a mechanical impulse repeater is arranged to be delayed until the association with the junction of a set of common metering control equipment to which the impulses are also repeated.

A further feature of the invention is that in a telephone system employing mechanical impulse repeaters for impulse repetition over junction lines a mechanical impulse repeater is provided with two sets of springs for retransmitting incoming impulses one set serving for repeating impulses over the junction line while the other serves for operating auxiliary equipment.

The invention will be better understood from the following description of one method of carrying it into effect, reference being had to the accompanying drawing which shows the circuit elements of a junction relay set JRS adapted to incorporate a mechanical impulse repeater arranged to operate in accordance with the invention. On the seizure of the junction relay set a start signal is extended to the allotter A which

selects an idle multi-metering equipment MME whereupon a rotary switch associated with this equipment hunts for the calling relay set. The circuit diagram has only been shown in sufficient detail to enable the principle underlying the invention to be understood.

It is assumed that use is being made of a mechanical impulse repeater or regenerator of the type disclosed in the J. W. McClew and C. R. Woodland Patent 2,183,461, issued January 30, 1940, which in addition to storage and subsequent transmission of the digits in corrected form also provides a controlled delay between successive digits transmitted in order to adequately cover the hunting time of the switches in the train. It will be understood however that the invention is not limited to a device of this precise construction.

Referring now to the drawing, it will be seen that on seizure of the junction relay set the subscriber's loop extended over the preceding selector or selectors operates relay A which in turn energises the slow-to-release relay B. Relay B thereupon applies earth to the common start lead S extending to the allotter A and thus operates relay ST while at the same time an impulsive circuit is prepared for the regenerator receiving magnet RM. Relay ST completes a self-interrupted driving circuit for the allotter magnet AM by way of the interrupter contacts 30

am whereupon the switch rotates in search of an idle multi-metering equipment which is marked by battery potential on the A2 bank. When a free outlet is reached relay G operates to cut the drive and at the same time due to its low resistance immediately guards the outlet seized. Relay G extends earth over the A1 wiper and bank to self-drive the junction relay set finder magnet JFM.

It will be appreciated that the allotter may be adapted in a well-known manner 40 to preselect an idle metering equipment in the intervals between calls but under heavy traffic conditions there would be insufficient time for preselection and the operation would be as described above. Immediately the finder switch JF 45 reaches the calling junction relay set which is marked by battery potential on the JF2 bank, relay SW operates to cut the drive and provides an immediate guard on the outlet seized. At the same time relay JF is operated and a circuit is 50 prepared for the meter-fee switch magnet MFM.

Meanwhile on reception of dialled impulses, relay A responds and repeats them to the regenerator receiving magnet RM which mechani- 55

cally stores the digits in a manner described in the specification previously referred to.

On operation of relay JF which signifies that an idle metering equipment is available, a circuit is completed to operate relay BY by way of the regenerator off-normal springs N, closed upon seizure of the mechanical impulse repeater, whereupon this relay connects one set of regenerator impulse springs IMP¹ to the outgoing junction and starts up the sending out of the digits stored in the regenerator. As each regenerated digit is transmitted over the junction the impulse springs IMP² transmit similar impulses to operate the multi-fee switch magnet MFM a corresponding number of times. The multi-fee switch is adapted to exercise control in accordance with the digits transmitted, for instance, as described in the R. Taylor and G. T. Baker application Ser. No. 134,500, filed April 2, 1937, whereupon after reception of the appropriate number of digits a signal is sent back to cause the required meter pulse lead to be connected up in the junction relay set. The common equipment is then disassociated from the junction relay set and is available for further common use. It will be appreciated that if a multi-metering equipment associates itself with a junction relay set before storage of all the dialled digits as would generally be the case, trains of impulses may be received and transmitted simultaneously by the regenerator.

In case the junction is worked on a bothway basis, on calls incoming over the junction the metering equipment would not be taken into use.

It may be pointed out that even if satisfactory impulse repeating conditions can readily be obtained the use of impulse regenerators can be justified on an economic basis in view of the simplification and saving in respect of the multi-metering equipment. If however the impulse repeating conditions are such as to require the use of impulse regenerators or the like in any event, the saving represented by the arrangement according to the invention is correspondingly greater.

I claim:

1. In a repeater, a relay group, a mechanical impulse storage and retransmitting device, a trunk line over which impulses are transmitted to said device, means in said relay group operated responsive to said impulses for controlling said mechanical device to store a plurality of said impulses, an outgoing trunk line, a set of impulsing contacts controlled by said mechanical device, and means for simultaneously connecting said impulsing contacts to said outgoing trunk line and for starting said mechanical device to operate said contacts after a plurality of impulses have been stored to retransmit all of the stored impulses over said outgoing trunk line.

2. In a telephone system, a mechanical impulse repeater arranged to store and retransmit impulses, an outgoing trunk line associated with said repeater, an incoming trunk line, common metering control equipment, means for controlling said repeater to store impulses received over said incoming trunk line, means for automatically controlling said common equipment to find and connect with said repeater, and means in said repeater operated responsive to said connection for controlling said repeater to start retransmitting said stored impulses over said outgoing trunk line and to said common equipment simultaneously.

3. In a telephone system, a plurality of me-

chanical impulse repeaters, a like plurality of associated trunk lines, common auxiliary equipment, means in said repeaters for storing impulses received over the incoming end of associated trunk lines, means in said repeaters for retransmitting the stored impulses over the outgoing end of said trunk lines, means controlled by an operated repeater for associating said common equipment therewith, and means in the operated repeater for delaying the retransmission of stored impulses until said common equipment is associated therewith, and means in the operated repeater operated responsive to association therewith of said common equipment for retransmitting said stored impulses to said common equipment and over the associated outgoing trunk line.

4. In a telephone system, a trunk line, a mechanical impulse repeater associated with said line, means in said repeater operated responsive to impulses received over the incoming end of said trunk line for storing said impulses, auxiliary equipment, means controlled responsive to the operation of said repeater for associating said auxiliary equipment with said repeater, means in said repeater operated responsive to the said association for starting the retransmission of stored impulses, two sets of springs for retransmitting the stored impulses, one of said set transmitting impulses over the outgoing end of said trunk line and the other of said sets transmitting impulses to said auxiliary equipment.

5. In a telephone system, a relay group, an outgoing trunk line associated with said relay group, a combined register and impulse transmitter associated with said relay group, an allotter, multi-metering equipment, a trunk line over which said relay group is seized and over which a plurality of series of impulses are transmitted to said relay group, means in said relay group operated responsive to said seizure for starting said allotter and operated responsive to said series of impulses for controlling said register in accordance with the impulses transmitted, means in said allotter for finding and seizing said multi-metering equipment, means in said metering equipment operated responsive to the seizure thereof for finding and connecting with said relay group, and means in said relay group operated responsive to said last connection for controlling said combined register and transmitter to simultaneously retransmit series of impulses corresponding to the series of impulses received to said metering equipment and over said outgoing trunk line.

6. In an automatic telephone system, a trunk relay group for use in completing a connection between a calling and a called subscriber, zone metering apparatus for controlling the operation of a calling subscriber's meter, switching apparatus for operatively associating said zone metering apparatus with said relay group, and means in said relay group for storing digit impulses and for retransmitting impulses in accordance with the digits stored to set automatic switches to complete the connection to the desired called subscriber and to set the zone metering apparatus accordingly in order that the calling subscriber's meter may be controlled thereby.

7. In an automatic telephone system, a trunk line, a trunk relay group associated with said line, a mechanical impulse storing and retransmitting device associated with said relay group, zone metering apparatus, an allotter for associating said metering apparatus with said relay

group, means responsive to the extension of a call over said trunk line to said relay group for starting said allotter to cause the connection of said metering apparatus with said relay group, 5 means in said relay group for operating said mechanical device to store impulses received over said trunk line, means for delaying the retransmission of said impulses until said metering apparatus is associated with said relay group, said 10 last means operated responsive to connecting of zone metering apparatus to said relay group to control said mechanical device to retransmit the stored impulses over the outgoing end of said trunk line to complete a connection and to simultaneously transmit said impulses to said zone 15 metering apparatus so that the calling subscriber may be properly charged for the connection according to the zone and duration of the call.

8. In a telephone system, a relay group, a mechanical impulse storage and retransmitting device, an incoming trunk line terminating in said relay group over which impulses are transmitted, means in said relay group operated responsive to said impulses for controlling said mechanical device to store said impulse, an outgoing trunk line extending from said relay group, zone metering apparatus, a finder switch for associating said zone metering apparatus with said relay group, 10 and means in said relay group for operating said mechanical device to retransmit the stored impulses over said outgoing trunk line operated responsive to said finder switch finding said relay group. 15

GEORGE THOMAS BAKER.
